[57] CLAIM

The ornamental design for a split lid box, as shown and described.

DESCRIPTION

FIG. 1 is a top and front perspective view of a split lid box showing our new design;
FIG. 2 is a side elevational view of one side of the box shown in FIG. 1, the other side being a mirror image of the one side shown;
FIG. 3 is a front elevational view of the box shown in FIG. 1;
FIG. 4 is a rear elevational view of the box shown in FIG. 1;
FIG. 5 is a top plan view of the box shown in FIG. 1; and,
FIG. 6 is a bottom plan view of the box shown in FIG. 1.

FIG. 1FIG. 2

FIG. 3***FIG. 4***FIG. 5

FIG. 6
